(No Model.)

E. A. COOPER.
HARNESS PAD TREE.

No. 296,140.

Patented Apr. 1, 1884.

UNITED STATES PATENT OFFICE.

EDWARD A. COOPER, OF BUFFALO, NEW YORK.

HARNESS-PAD TREE.

SPECIFICATION forming part of Letters Patent No. 296,140, dated April 1, 1884.

Application filed June 7, 1883. (No model.)

To all whom it may concern:

Be it known that I, EDWARD A. COOPER, of the city of Buffalo, in the county of Erie and State of New York, have invented a new and useful Improvement in Harness-Pad Trees, of which the following is a specification.

This invention relates to an improvement in that class of harness-saddles in which the yoke is connected to the pad-frame by a joint which permits one part to rock on the other in being adjusted to the horse.

The object of my invention is to provide a simple and efficient device for attaching the parts of the saddle together; and my invention consists to that end of the improvements which will be hereinafter fully set forth, and pointed out in the claims.

In the accompanying drawings, Figure 1 is a side elevation of a harness-saddle provided with my improvements. Fig. 2 is a vertical section of one-half of the saddle at right angles to Fig. 1. Fig. 3 is a side elevation, Fig. 4 an edge elevation, and Fig. 5 a perspective view, of the lower pad-plate. Fig. 6 is a side elevation of the upper pad-plate. Figs. 7 and 8 are cross-sections in lines xx and yy , Fig. 2, respectively. Fig. 9 is an inside elevation of one end of the yoke. Fig. 10 is an edge elevation of the same and connecting parts. Fig. 11 is a plan view, and Fig. 12 an end view, of the pivoted nut.

Like letters of reference refer to like parts in the several figures.

A represents the yoke, of which only one end is shown in the drawings.

B represents the upper pad-plate, and C the lower pad-plate, both together constituting the pad-frame.

D represents the saddle-flap or skirt-strap, secured with its upper end between the pad-plates B and C.

E represents the terret, whereby each end of the yoke is secured to the adjacent pad-frame. Each end of the yoke is constructed on its under side with two convex bearings, ff , preferably formed in the side flanges, f' , of the yoke, as shown, on opposite sides of the opening f'' , through which the terret-screw d passes. These bearings are seated upon convex supports g , which are formed on the up-

per side of the lower pad-plate, C. The supports g are arranged so far apart on the plate C as to receive between them a screw-nut, H, into which the pad-screw d screws. The nut H is provided with pivots h , arranged across the yoke and seated in recesses h on the under sides of the supports g , whereby the nut H is held against turning, and at the same time permitted to rock as the end of the yoke rocks on the supports g in being adjusted. The lower plate, C, is constructed with an opening, i , between the supports g and the upper plate, B, with a corresponding opening, i' , which permits the requisite limited movements of the nut on its pivots.

k represents a hook or projecting lip formed on the upper side of the lower plate, C, and k' an opening formed in the upper plate, B, for the reception of the lip k .

l represents the pad-screw, whereby the lower ends of the plates B and C are secured together. The screw-threaded end of the screw l engages in a nut, l' , secured to the under side of the plate C, in the usual manner.

m represents a stud or pin formed on the under side of the plate B, between the terret E and the pad-screw l , and adapted to enter an opening in the skirt-strap or saddle-flap E, which is secured between the plates B and C, thereby more firmly securing the same in place.

The nut H is free to rock on its pivots, and the yoke A is free to rock by means of its concave bearings f on the convex supports g , whereby the pad-frame and the yoke are enabled to adjust themselves to suit the form and size of the horse, while the yoke is at the same time firmly connected to the pad-plate by the concave bearings f and convex supports g . The pivots h of the nut may be beveled off on their lower sides, as represented in Fig. 10, to give the pivots more freedom of movement in their seats.

The saddle-flap or skirt-strap D is secured between the metallic plates B and C, forming the pad-frame, whereby a rigid and reliable connection of the saddle-flap with the pad-frame is secured. The nut H being inserted in its seat from below, it is covered by the pad proper, and thereby guarded against acci-

dental displacement or loss. The plates B and C are each cast complete of malleable iron or other suitable metal, and are readily secured together and to the saddle-flap by the hook-joint at the upper ends of the plates and the pad-screw at the lower ends of the plates.

5 I claim as my invention—

1. The combination, with the yoke A, provided on its under side with concave bearings f, of the pad-plate C, provided on its upper side with convex supports g, engaging in the bearings f, and having recesses h' on their un-

der side, a nut, H, provided with pivots h, engaging in the recesses h', and a pad-screw, d, whereby said nut is attached to the yoke, substantially as set forth.

2. The combination, with the plate C, provided with a lip, k, of the plate B, having an opening, k', and a stud, m, and the fastening-screw l, substantially as set forth.

EDWARD A. COOPER.
